UNITED STATES PATENT OFFICE.

WALTER W. BICKEL AND HALLEY E. BROWN, OF DES MOINES, IOWA.

CHIMNEY-TOP.

1,390,269.

Specification of Letters Patent. Patented Sept. 13, 1921.

Application filed May 17, 1920. Serial No. 381,932.

To all whom it may concern:

Be it known that we, WALTER W. BICKEL and HALLEY E. BROWN, citizens of the United States, residing in Des Moines, 5 county of Polk, and State of Iowa, have invented a new and useful Improvement in Chimney-Tops, of which the following is a specification.

The object of this invention is to provide 10 means for expanding and contracting a chimney-top to fit chimneys of various transverse dimensions.

A further object of this invention is to provide an improved construction for chimney-tops having separable embracing members arranged in telescoping relation to each other and adapted to be locked together in various positions in respect to expansion or contraction thereof.

20 A further object of this invention is to provide means for bridging spaces in an expandible and contractible chimney top.

Our invention consists in the construction, arrangement and combination of elements 25 hereinafter set forth, pointed out in our claims and illustrated by the accompanying drawing, in which—

Figure 1 is a side elevation of one embodiment of our invention, the dotted lines 30 indicating expansion thereof. Fig. 2 is a central cross-section of the same. Fig. 3 is a central cross-section of embracing elements of the device.

Fig. 4 is a cross-section on the indicated 35 line 4—4 of Fig. 5, and Fig. 5 is a plan of a bridging device susceptible of being substituted for parts of the device shown in Figs. 1, 2 and 3.

In the construction of the device as 40 shown in Figs. 1, 2 and 3, the numeral 10 designates a plate, preferably made of sheet metal, generally flat and plane in form, square in shape and of a size to overlay the top of a chimney of relatively small trans- 45 verse dimensions. The plate 10 is formed with a centrally located hole 11, of any suitable shape, said hole being shown square in the drawing, adapted to register and substantially correspond in transverse di- 50 mension with the flue of the chimney mentioned. One or more flanges 12 are formed on the plate 10, at the margin of the hole 11, and extend upwardly from said plate, said flanges forming and providing a base, 55 or collar, for a cowl or flue extension (not shown), whereby said plate may be secured

to and support said cowl. The plate 10 is formed with re-curved or folded flanges 13 on its outer margins, which flanges lie below and parallel with said plate. Embracing members are provided, preferably four in number, one for each corner of the plate. Each embracing member is formed with an upright wall 14, bent substantially at right angles adjacent its center and adapted to 60 embrace a corner of a masonry chimney (not shown), and a horizontal flange 15 integral with and extending inwardly from the upper margin of said wall. The wall 14 and flange 15 preferably are formed of 65 one piece of sheet metal by bending, the flange being notched at its center in a common manner to permit said bending. When the embracing members are mounted for use with the plate, the end portion of adjacent members overlap as to their walls and the flanges of said members extend, 70 slidingly, within flat pockets formed by the re-curved or folded flanges 13, as shown in Fig. 2. Some of the flanges 15 of the embracing members are offset as shown at 75 16 in Fig. 3 so that the end portion of an adjacent flange 15 may overlap thereon when the device is contracted and the walls 14 are within an outline circumscribed by 80 the margin of the plate 10 in fitting a relatively small chimney. Two different means are shown for connecting the walls 14 of separate embracing members to give 85 them gripping and embracing effect relative 90 to the chimney. One such means comprises angle-ears 17, 18 fixed to adjacent end portions of overlapping or overlappable walls 14, said ears being formed with registering 95 openings, and stove-bolts 19 mounted in said openings and employed to connect the ears and draw the ears, and consequently the walls, together. The other of said means comprises a strap 20, secured by a rivet 21 to one wall, and extending across 100 the adjacent ends of two walls 14 and passing beneath a clip or keeper 22 struck out of the adjacent wall, the strap overlapping the end of the wall carrying the clip and being adapted to be bent outward and 105 folded on the clip, at its outer end, to hold the respective walls or embracing members in a given relative position. One form of connecting means may be used on the shorter sides of the expanded device and 110 the other form of connecting means may be employed on the longer sides of the ex-

panded device, or the same may be used selectively.

In the construction according to Figs. 4 and 5, the plate 10^a is formed without the 5 recurved or folded flanges 13 and a duplicate plate 10^b, except that the flanges 12 are omitted, is located beneath and parallel with the plate 10^a and spaced therefrom by means of bars 23 located adjacent to margins of the 10 holes 11. The plates 10^a, 10^b and bars 23 are connected by stove-bolts 24 in suitable 15 locations. Such construction provides flat pockets 25 adapted to receive flanges 15 and 15^a of embracing members as above described in assembling the device for use.

Because of the formation of the base plate with flat pockets, of either form, and the formation of the embracing members with flanges adapted to enter said pockets, and the 20 provision of means for adjustably connecting the walls of the embracing members, a complete device is produced which protects the top of a chimney from injurious effects of the elements and centers the out-going 25 smoke and provides a base for a cowl.

We claim as our invention—

1. A chimney-top comprising a base plate formed with flat pockets and a central opening, embracing members formed with flat 30 members adapted to slide in said pockets, and means for connecting said embracing members.

2. A chimney-top comprising a sheet-metal plate formed with a central opening

and also formed with outwardly-opening 35 flat pockets, embracing members formed with flanges adapted to slide in said pockets, and means for adjustably connecting said embracing members.

3. A chimney-top comprising a sheet-metal plate formed with a central opening, and also formed with flanges adjacent to 40 said opening, and also formed with outwardly-opening flat pockets at its outer margins, embracing members formed with 45 flanges adapted to slide in said pockets, and means for adjustably connecting said embracing members.

4. A chimney-top comprising a plate formed with a central opening and also 50 formed with recurved or folded flanges at its margins, said flanges lying parallel with said plate and forming outwardly-opening pockets, and embracing members adapted to embrace the corners of a chimney and 55 formed with flanges adapted to slide in said pockets, and means for adjustably connecting said embracing members.

5. A chimney top comprising a plate having flanges and embracing members adjustably engaging said flanges, said members being formed with walls overlapping at 60 their ends, in combination with connecting means extending across the overlapping ends of the walls and adjustably connecting the 65 same.

WALTER W. BICKEL.
HALLEY E. BROWN.
